UNITED STATES PATENT OFFICE.

JAMES FLETCHER, OF DETROIT, MICHIGAN.

THERMOSTATIC CONTROL DEVICE FOR CIRCULATING SYSTEMS.

Application filed March 12, 1923, Serial No. 624,683. Renewed June 3, 1926.

The invention relates to thermostatic control devices for circulating systems and is particularly adapted for use in regulating the flow of the cooling medium of an internal combustion engine. The invention has for one of its objects the provision of a very simple construction of control device which is of light weight and comprises but few parts which may be readily manufactured and assembled at a low cost. Other objects of the invention reside in the novel features of construction as more fully herein-after set forth.

In the drawings:

15 Figure 1 is a diagrammatic view of a portion of a motor vehicle including the internal combustion engine and radiator with my thermostatic control device applied;

20 Figure 2 is a longitudinal section through the thermostatic control device;

Figure 3 is a cross section on the line 3—3 of Figure 2.

25 My thermostatic control device is shown applied to a motor vehicle having a water-cooled internal combustion engine 1 and the radiator 2, this device being located in the upper water connection between the engine and radiator.

30 The casing of the thermostatic control device comprises the cup-shaped section 3 and the cooperating section 4 secured thereto. The cup-shaped section has the axial opening 5 in its end surrounded by the cylindrical flange 6 to which an end of one of the hose sections of the upper water connection between the engine and radiator is secured by suitable means. The cooperating casing section 4 comprises the end plate 7 and the intermediate plate 8, the end plate having the axial opening 9 with the cylindrical flange 10 surrounding the same and to which an end of one of the hose sections of the upper water connection is secured by suitable means. The intermediate plate 8 is integral with the end plate 7 and held in spaced parallel relation thereto by means of the integral radial webs 11 extending between the plates. The intermediate plate is provided with the radial projections 12 upon its periphery which engage in transverse grooves 13 in the inner periphery of the cup-shaped section 3 to guide the intermediate plate during the assembly and securing together of the section. With the arrangement as thus far set forth, the en-

gine cooling medium, such as water, enters the casing of the thermostatic control device through the opening 9 in the end plate 7, passes through the radial or transverse passage between the plate 7 and intermediate plate 8, then passes between the peripheries of the intermediate plate 8 and the cup-shaped section 3 into that portion of the cup-shaped section beyond the intermediate plate and finally out through the opening 5 in the end of the cup-shaped section.

To secure the cooperating section 4 of the casing to the cup-shaped section 3, the end of the inner periphery of the latter is machined to form an annular shoulder 14 against which the end plate 7 of the cooperating section abuts, this end plate having a press-fit within the machined portion to form a water-tight seal. The shoulder positions the end plate 7 so that its outer face is located inwardly beyond the outer end of the cup-shaped section, which latter is peened over by a suitable tool to firmly hold the end plate against the shoulder and at the same time to assist in forming a better water-tight seal between the casing sections.

For controlling the flow of the cooling medium as its temperature rises and falls, I have provided the freely movable annular thermostatic valve 15 having overlapping ends and mounted upon the cooperating casing section 4. The adjacent faces of both the end plate 7 and intermediate plate 8 are formed with corresponding annular shoulders 16 and 17 respectively forming seats engageable by the thermostatic valve. As the temperature of the water entering the thermostatic control device increases, this thermostatic valve expands so that its diameter becomes greater than the diameter of the intermediate plate, at which time a portion of the water is allowed to pass through the thermostatic control device. As the temperature of the water increases and the expansion of the thermostatic valve increases, its diameter continues to increase until it lies adjacent to the inner periphery of the cup-shaped section 3, it being guided by means of the radial projections upon the intermediate plate and the end plate. Since these radial projections extend into grooves in the cup-shaped section, the thermostatic valve cannot engage between the ends of these radial projections and the inner periphery of the cup-shaped section.

Both the cup-shaped section and the co-

operating section of the casing are preferably die cast so that as a consequence the cost of manufacture of these parts is considerably decreased. Furthermore, the machining operations upon both the sections are small in number and very simple, and their assembly may be readily accomplished at a small cost. Still another feature is that the weight of the device is relatively small so that no support other than that afforded by the hose sections of the upper water connection is necessary.

What I claim as my invention is:

1. In a thermostatic control device, the combination with a casing comprising a section having a passage therein, a second section secured to said first-mentioned section and having a passage therein extending transversely of said first-mentioned passage and adapted to communicate therewith, and a valve upon said second section readily responsive to differential temperatures for controlling communication between said passages.
2. In a thermostatic control device, the combination with a casing comprising a section having a passage therein and a second section secured to said first-mentioned section and comprising an end plate and an intermediate plate spaced from said end plate and located within said first-mentioned section, said intermediate plate having a portion of its periphery spaced from the interior periphery of said first-mentioned section, and a thermostatic valve cooperating with said end and intermediate plates for controlling communication between the space intermediate said plates and the passage in said first-mentioned section.
3. In a thermostatic control device, the combination with a casing comprising a section having a passage therein and a second section secured to said first-mentioned section comprising an end plate and an integral intermediate plate located within said first-mentioned section and having a portion of its periphery spaced from the interior periphery thereof, said integral intermediate plate being spaced from said end plate to form a passage in said second section extending transversely of said passage in said first-mentioned section, and an annular thermostatic valve upon said second section and cooperating with said end and intermediate plates for controlling communication between said passages.
4. In a thermostatic control device, the combination with a casing comprising a cup-shaped section having a passage in its end, and a second section secured to said cup-

shaped section and comprising an end plate having a passage therein and an integral intermediate plate within said cup-shaped section and having a portion of its periphery spaced from the interior periphery thereof, said intermediate plate being spaced from said end plate to form a passage communicating with said passage in said end plate and adapted to communicate with said passage in said cup-shaped section, and an annular thermostatic valve upon said second section and cooperating with said end and intermediate plates for controlling communication between said passages in said sections.

5. In a thermostatic control device, the combination with a casing section having an opening therein, of a second casing section secured to said first-mentioned casing section and having an opening therein, said second casing section having a plate intermediate said openings, and a loosely mounted thermostatic valve cooperating with said plate for controlling the communication of said openings with each other.

6. In a thermostatic control device, the combination with a cup-shaped casing section having an opening in its end, of a second casing section secured to said cup-shaped section and comprising an end plate having an opening therein and a plate spaced interiorly from said end plate and located within said cup-shaped section and having a portion of its periphery spaced from the interior periphery of said cup-shaped section, said plates having corresponding annular seats on their adjacent faces, and an annular thermostatic valve adapted to engage the corresponding seats upon said plates.

7. In a thermostatic control device, the combination with a two-part casing comprising a cup-shaped section having an opening in its end and a section having an end plate engaging the inner walls of the outer end of said cup-shaped section, and having an opening therein and an integral intermediate plate within said cup-shaped section and spaced from said end plate, said intermediate plate having a portion of its periphery spaced from the inner periphery of said cup-shaped section for placing the interior of said cup-shaped section therebeyond in communication with the space between said plates, and a thermostatic valve controlling the above-mentioned communication.

In testimony whereof I affix my signature.

JAMES FLETCHER.
